UNITED STATES PATENT OFFICE.

ARTHUR KORN, OF BERLIN-CHARLOTTENBURG, GERMANY.

TELAUTOGRAPHIC TRANSMISSION.

Application filed March 1, 1924, Serial No. 696,228, and in Great Britain September 6, 1923.

In the method of telautographic transmission, as commonly practised heretofore the handwriting, drawing or the like to be transmitted by means of the Bakewell transmitter is deposited by means of non-conducting material upon a metal foil which is wound upon a cylinder and along which a pointed metal feeler is made to move which, upon the rotation of said cylinder, describes a close helical line along the cylinder. Whenever the pointed end engages with a conducting portion of the foil an electric circuit is closed and a current established, which is interrupted, when the metal point engages with a non-conducting portion. The currents are transmitted to the receiver by a telegraphic conduit, where they serve for the reconstruction of the picture.

In the invention about to be described the successively occurring current impulses of the Bakewell transmitter are utilized at the transmitting station for the automatic production of a typed telegram or of a telegraphic perforated strip from which at the receiving station the picture may be reconstructed. It has already been suggested by the inventor in connection with transmitters possessing five pointed metal feelers instead of only one such metal point, to have the feeler run in contact with the transmitting foil, so that five lines of the picture at the transmitting station in succession are simultaneously in engagement with the feeler. In certain small time intervals, for instance ten times in a second, the electric tension in the method referred to was transmitted to the Bakewell cylinder, and in accordance with the closing of the circuit occurring in the first, 2nd, 3rd, 4th or 5th line or failing to occur a hole was punched out in the first, second, third, fourth or fifth line respectively upon a perforation strip containing five lines, or a type corresponding to this combination of five lines was printed. The telegram received at the receiving station was written down by means of a special type writing machine in which the letter types are replaced by types corresponding to the five-lines perforation strip; so that

there would for instance correspond to the following combination of holes

the following form of types

With this method it has, however, been found that it is very difficult to cause the five metal points to feel along the transmitting foil at sufficiently narrow distances from each other.

In order to overcome this difficulty only one feeling pointer is employed in accordance with the present invention, five successive feeling operations being used for the production of a combination of holes or of a letter type.

The invention will be more fully described with reference to the accompanying drawing showing by way of example, one form of embodiment of the principles of my invention.

As shown in the drawing, upon the metal cylinder 1 there is mounted a metal foil upon which the design is produced with non-conducting material; upon the metal foil a feeling pointer 2 is adapted to move which feels along the metal foil in helical lines similar to the stylus of a phonograph. For the production of each combination of holes of the registering perforation strip five successively occurring feeling engagements have to be performed within a certain small time interval.

During the time in which these five feeling engagements of the pointer are being

carried out, a non-conducting wheel 3 makes one rotation in the direction of the arrow, the wheel carrying on its front end surface seven conducting sectors 4, 5, 6, 7, 8, 9, 10 which are adapted to establish an electric contact with the ends of seven metallic springs 11, 12, 13, 14, 15, 16, 17. The contact piece 4 is electrically connected to the contact pieces 5 to 10.

10 By means of the wheel 3 and the springs 11 to 17 five polarized relays 18, 19, 20, 21, 22 are adapted to be operated, and in such a manner that in the first feeling operation the relay 18 is excited, provided the feeling pointer 2 makes contact with a conducting portion of the foil. In the second feeling operation the relay 19 is excited, and so on in succession.

Upon the commencement of each rotation 20 of the wheel 3 all the relays should be restored to their position of rest. With this point in view the battery 23 with the terminals 24, 25 is substantially centrally subdivided, and a circuit is branched off at 26; 25 from the terminal 24 a line conduit 27 leads to a sliding contact 28 of the Bakewell cylinder 1, and when the feeling pointer is on a conductive portion of the foil a current passes through said pointer 2 to the spring 30 11. A conduit 29 leads from the terminal 25 to the spring 17, and from the pointer 26 a common line conduit 30 leads to the terminals of the windings of the relays 18 to 22, while from the other terminals of the windings of the relays the conductors 31, 32, 33, 34 and 35 lead respectively to the springs 12, 13, 14, 15, 16. When the segment 5 is moving past the springs the spring 17 is connected to 12, 13, 14, 15 and 16, and the 35 relays are restored to the position of rest by a current impulse of the battery portion 26, 25. If the segments 6 and 4 move past the springs 11 and 12 the relay 18 is operated upon the feeler 2 making contact with the foil; relay 19 is operated, when the segments 45 7 and 4 move past the springs 11 and 13; relay 20 is operated by the movement of the segments 8 and 4 on the springs 11 and 14; relay 21 is operated by the movement of the segments 9 and 4 along the springs 11 and 50 15, and the relay 22 is operated by the movement of the segments 10 and 4 on the springs 11 and 16. Between the ends of the segments 4 and 5 a non-conducting sector of 55 about one ninth of the circular surface is inserted. While this sector is moving past the springs the relays 18 to 22 remain in the position produced by the five feeling operations, and may be used in this position for the punching of perforation strips or for 60 the printing of types and the like.

In the arrangement hereinbefore described reference is made to the operation of the Siemens rapid-telegraph with perforation of

perforation strips with five lines or to the 65 operation of the Siemens translator with the corresponding printing of letters. The new method may, however, also be used by a similar procedure for the operation of other rapid telegraphs and multiple telegraphs. If 70 the production of perforated strips is intended this perforation (at each rotation of the member 3 one combination of holes) may be directly effected by means of five perforating magnets in accordance with the 75 adjustment of the relays 18 to 22; in case the printing of types or letters is intended it is necessary to add for the operation of the five polarized relays 36, 37, 38, 39 and 40 of the printing apparatus of the Siemens 80 rapid telegraph a non-conducting wheel 41 with the imbedded conducting segments 42, 43, 44, 45 and 46 of which a segment 45 is electrically connected to 46, and segment 42 is connected to 44. The wheel 41 rotates together with the wheel 3 in the direction of the arrow in such a manner that the free sector of wheel 3 passes over the ends of the springs 11 to 17, when the similar sector on the wheel 41 with the segments 42 to 46 90 passes over the five metallic springs 47, 48, 50 and 51. During this short time the relays 36 to 40 are influenced, while the relays 18 to 22 remain in their adjusted position. During the rest of the time the relays 36 to 40 95 remain in their adjusted position adapted for the printing of the letter corresponding to the five feeling operations.

A conductor 52 leads from the relay levers 53, 54, 55, 56 and 57 of the relays 18 to 22 100 to each one terminal of each of the windings of the relays 36 to 40; 58, 59, 60, 61 and 62 are the resting contacts of the relays 18 to 22, and 63, 64, 65, 66 and 67 indicate the working contacts of these relay levers which are 105 connected to the point 26 by the conductor 73, and with which the relay levers 53 to 57 are made to engage upon the operation of said relays. Furthermore, a connecting line 68 leads from 26 to the spring 47, 110 a conductor 69 from 25 to spring 48 and conductor 70 from 24 to spring 49. The common terminals of the windings of relays 36 to 40 are connected to the spring 50 by a conductor 71. From contacts 58, 59, 60, 61, 115 62 a line conduit 72 leads to spring 51.

Upon the sectors 42, 43, 44 of the wheel 41 moving past the ends of the springs 47, 48, 49, 50 and 51 the relays 36 to 40 are returned to their position of rest, and upon the sectors 120 45 and 46 of the wheel 41 moving across the ends of springs 48 and 50 the relays 36 to 40 are adjusted to operative position.

What I claim is:

1. Telautographic transmission means for 125 hand writing, drawing, and the like, comprising, a single feeling pointer, a plurality of relays connected for operation by the

single feeling pointer, a partially conducting support over which the pointer is movable and containing the object to be transmitted, contacting means arranged to electrically connect the relays with the pointer, and means controlled by the relays for producing a record.

2. Telautographic transmission means for hand writing, drawing, and the like, comprising, a single feeling pointer, a plurality of relays connected for operation by the single feeling pointer, a partially conducting support over which the pointer is movable and containing the object to be transmitted, contacting means arranged to electrically connect the relays with the pointer, and means controlled by the relays for producing a record, and separate contact elements on the contacting means so that the feeler engages with the object to be transmitted and with the partially conducting support thereof, a plurality of times in succession, for the production of a record which is the combination with the relays of the lines from the separate contact elements to the relays.

3. Telautographic transmission means for hand writing, drawing, and the like, comprising, a single feeling pointer, a plurality of relays connected for operation by the single feeling pointer, a partially conducting support over which the pointer is movable and containing the object to be transmitted, contacting means arranged to electrically connect the relays with the pointer, and means controlled by the relays for producing a record, and separate contact elements on the contacting means so that the feeler engages with the object to be transmitted and with the partially conducting support thereof, a plurality of times in succession, for the production of a record which is the combination with the relays of the lines from the separate contact elements to the relays, the partially conducting support comprising, a Bakewell cylinder bearing the object to be transmitted in non-conducting material.

4. Telautographic transmission means for hand writing, drawing, and the like, comprising, a single feeling pointer, a plurality of relays connected for operation by the single feeling pointer, a partially conducting support containing the object to be

transmitted, contacting means arranged to electrically connect the relays with the pointer, and means controlled by the relays for producing a record, the feeling pointer and the support being movable in relation to each other, the contacting means including, a rotatable contact plate electrically connected to the pointer, a plurality of staggered electrically interconnected conducting segments on the plate for selectively placing the relays in operation.

5. Telautographic transmission means for hand writing, drawing, and the like, comprising, a single feeling pointer, a plurality of relays connected for operation by the single feeling pointer, a partially conducting support containing the object to be transmitted, contacting means arranged to electrically connect the relays with the pointer, and means controlled by the relays for producing a record, the feeling pointer and the support being movable in relation to each other, the contacting means including, a rotatable contact plate electrically connected to the pointer, a plurality of staggered electrically interconnected conducting segments on the plate for selectively placing the relays in operation and an electrically insulated segment on the plate.

6. Telautographic transmission means for hand writing, drawing, and the like, comprising, a single feeling pointer, a plurality of relays connected for operation by the single feeling pointer, a partially conducting support containing the object to be transmitted, contacting means arranged to electrically connect the relays with the pointer, and means controlled by the relays for producing a record, the feeling pointer and the support being movable in relation to each other, the contacting means including, a rotatable contact plate electrically connected to the pointer, a plurality of staggered electrically interconnected conducting segments on the plate for selectively placing the relays in operation and an electrically insulated segment on the plate, a second contact plate connected in parallel with the first contact plate, and provided at the point corresponding to the insulated segment, with telegraph operating contacts.

In testimony whereof I have signed my name this 23rd day of January, 1924.

ARTHUR KORN.
